UNITED STATES PATENT OFFICE.

ABRAHAM B. APPLER, OF WATERVLIET, AND JOHN T. McGINITY, OF GREEN ISLAND,
NEW YORK.

SAFETY RETAINING DEVICE.

1,201,230.

Specification of Letters Patent. Patented Oct. 17, 1916.

Application filed December 27, 1915. Serial No. 68,719.

To all whom it may concern:

Be it known that we, ABRAHAM B. APPLER and JOHN T. McGINITY, citizens of the United States, residing at Watervliet, county 5 of Albany, State of New York, and Green Island, in the county of Albany and State of New York, respectively, have invented certain new and useful Improvements in Safety Retaining Devices, of which the following is a specification.

Our invention relates to a device comprising a plate and a spring adapted to act as a safety device for holding various parts of machinery securely in place, and among 15 the objects in view is to provide a device of the character described which will be extremely simple and inexpensive in construction and efficient in operation, the same being adapted to hold various parts securely in 20 place, such as lubricant cellars in journal boxes of locomotives and cars, piping and the like on locomotives, etc.

The invention consists in the novel construction, arrangement and combination of 25 parts as hereinafter fully described, illustrated in the drawings and pointed out in the appended claims.

In the drawings: Figure 1 is a vertical sectional view of a journal box of a locomotive 30 showing our invention in connection therewith. Fig. 2 is a vertical sectional view taken at right angles to Fig. 1. Fig. 3 is a horizontal sectional view taken on a line just above the safety plate and showing the 35 spring in position. Fig. 4 shows a plan view and an edge view of the spring.

While we have illustrated in the drawings, as an example only, the application of our 40 invention to the journal box of a locomotive, yet it will be understood that the device is equally well adapted for application to various other parts of machinery or structures.

e indicates a journal box of a locomotive, 45 within which box is arranged a lubricant cellar *f*, containing suitable lubricant *f'*. The cellar *f*, is movably arranged in the box *e*, and its upper edges are adapted to bear against shoulders *g*, formed on the journal 50 box, which shoulders thus limit the upward movement of the cellar.

Integral with the box *e*, are the four depending lugs *d*, which are formed each with a depression *h*, forming a horizontal bearing 55 surface *j*, upon which the plate *a*, is

adapted to rest, and also forming a shoulder *h'*, which shoulders constitute abutments between which the plate is confined and prevented from moving out of place both sideways and endwise. Each of the lugs is 60 further provided with a horizontal groove *c*, lying in a horizontal plane slightly above the plate when the latter is in position.

The bottom of the cellar is arched upwardly as at *i*, and against the under surface 65 of the arch bears the curved or bowed spring *b*. This arch prevents the lubricant cellar from moving along the upper surface of the spring and thereby retains the lubricant in its proper relation to the surface to be lubri- 70 cated, as an axle journal *l*, even though the bolts which hold the lubricant cellar in place have become broken or lost. The lubricant cellar is further provided on opposite sides of its arched portion with depending lugs 75 *v* which lie on opposite sides of the spring *b*, to assist in holding it in place, as seen more clearly in Fig. 2. The spring *b*, is se- 80 cured at one end by studs, bolts or rivets *b'* to the plate *a*. The plate *a*, is applied by pushing it along the grooves *c*, thereby compressing the spring and finally drops into the depressions *h*, in the lugs and rests upon the surfaces *j*. By reason of the spring be- 85 ing under compression the same acts to hold the lubricant box securely in place and the plate *a*, is also held firmly in its position. In removing the plate it is raised against the compression of the spring and then pulled out along the grooves.

k are bolts which pass through apertures in the lugs *d*, and the lubricant cellar to retain the latter in place. While we may use such bolts in connection with our retaining device, yet it is not our intention to so re- 95 strict the use of our device, and the bolts *k*, may be dispensed with, since by the use of the safety device they are not required.

What we claim and desire to secure by Letters Patent is:

1. The combination with a journal box provided with depending lugs, each of which has a horizontal groove and a depression forming a bearing surface and a shoulder, of a lubricant cellar arranged within 105 the journal box, a plate removably seated upon the bearing surfaces of the lugs and confined intermediate the shoulders thereof, and a spring carried by the plate and bearing against the cellar.

2. The combination with a journal box provided with depending lugs, of a lubricant cellar arranged within the journal box, the lower or bottom portion of said cellar being arched, a plate seated in the lugs, and a bowed spring carried by the plate and seating within the arched portion of the cellar and bearing against the underside thereof.
3. The combination, with a journal box provided with depending lugs, of a lubricant cellar arranged within the journal box, the lower or bottom portion of said cellar being arched and having depending lugs on oppo-

site sides of the arched portion, a plate seated in the lugs of the journal box, and a bowed spring carried by the plate and seating within the arched portion of the cellar and bearing against the underside thereof.

In testimony whereof we affix our signatures in presence of two witnesses.

ABRAHAM B. APPLER.
JOHN T. McGINITY.
